UNITED STATES PATENT OFFICE.

LOUIS GARNIER, OF SAN DIEGO, CALIFORNIA.

SACK-HOLDING AND WEIGHING DEVICE.

1,146,061.

Specification of Letters Patent. Patented July 13, 1915.

Application filed September 14, 1914. Serial No. 861,696.

To all whom it may concern:

Be it known that I, LOUIS GARNIER, a citizen of France, residing at San Diego, in the county of San Diego and State of California, have invented certain new and useful Improvements in Sack-Holding and Weighing Devices, of which the following is a specification, reference being had to the accompanying drawings.

10 This invention relates to certain improvements in sack holding and weighing devices, and the object of the invention is to provide a device of this general character having novel and improved means whereby a sack or the like may be conveniently and effectively held in position to be filled and whereby the weight of the matter placed within the sack or the like may be determined with facility and accuracy.

20 The invention consists in the details of construction and in the combination and arrangement of the several parts of my improved device, whereby certain important advantages are attained and the device is rendered simpler, less expensive and otherwise more convenient and advantageous for use, all as will be hereinafter more fully set forth.

The novel features of the invention will 30 be carefully defined in the appended claims.

In order that my invention may be the better understood, I will now proceed to describe the same with reference to the accompanying drawings, wherein—

35 Figure 1 is a perspective view of an apparatus constructed in accordance with an embodiment of my invention; Fig. 2 is an elevational view of the device as disclosed in Fig. 1; Fig. 3 is a sectional view taken substantially on the line 3—3 of Fig. 1; Fig. 4 is a sectional view taken substantially on the line 4—4 of Fig. 1; Fig. 5 is a sectional view taken substantially on the line 5—5 of Fig. 1; Fig. 6 is a sectional view taken substantially on the line 6—6 of Fig. 2; and Fig. 7 is a sectional view taken substantially on the line 7—7 of Fig. 2.

40 As disclosed in the accompanying drawings 1—1 denote the legs of the frame for my improved apparatus and, as herein disclosed, are three in number and are constructed of pipe sections, the lower extremities of which being offset to provide the feet 2, said feet

being connected with a spider 3 through the medium of the adjustable members 4, 55 said members 4 being adapted to provide a means whereby the device, hereinafter to be more fully described, may be sustained in a perfectly vertical position upon an uneven 60 surface.

The lower portion of the device, as herein set forth, is substantially triangular in form so as to provide what may be termed an open front. The pipe members forming the legs 1 have their upper extremities 5 offset 65 and secured to the vertical tubular members 6 of the device. These tubular members 6 are connected at spaced intervals by substantially semi-circular members 7 secured to the members 6 in any desired manner.

70 The uppermost member 7, or brace as it may be termed, is provided upon its outer face with a buffer 8, the same comprising an elongated member having its inner edge or face rounded to correspond with the contour 75 of the adjacent edge or face of the member 7. The member or buffer 8 is provided adjacent its ends with the openings 9 through which extend the headed pins 10, the latter being attached to the said upper brace or 80 support 7. Interposed between the inner edge or face of the member or buffer 8 and the adjacent member or support 7 and surrounding the pins 10 are the helical springs 85 11 which are adapted to exert such tension between the buffer or member 8 and the adjacent member or brace 7 as to force said member or buffer 8 outwardly or away from the member or members 7 and into contact 90 with the heads of the pins 10.

95 The elements, hereinbefore described, comprise the frame proper for the device, and each of the tubular members 6 adjacent its upper and open end is provided with the inwardly disposed annular shoulder 12 adapted to serve as a support for the disk 14 to which is attached the upper extremity of a helical spring 15. The lower extremity of the spring 15 is closed and arranged therein is a rod 16 engaged with the closed 100 extremity of the spring and having its upper extremity loosely disposed through the disk 14 and in threaded engagement with a socket member 17.

105 The socket member 17 has provided adjacent its lower extremity the annular periph-

eral race-way 18 adapted to receive the anti-friction members 19, herein disclosed as spherical bodies. The anti-friction members 19 are adapted to engage with the inner face 5 of the tubular member 6, for purposes which are believed to be self-evident.

The springs 15 normally force the socket members 17 beyond the upper or open ends of the tubes 6, and each of such socket members is provided with a sleeve 20, which surrounds the tube and serves as a protection for the spring as well as for the anti-friction members, as is believed to be clearly apparent.

15 The upper extremity of each of the socket members 17 is provided with an offset radiating arm 21 suitably connected with the flanged annular member 22. The member 22 has its upper flanged portion 23 provided with a plurality of spaced openings 24 with which are adapted to coact the spaced studs 25 carried by the annular clamping member 26 adapted to overlie the upper flanged portion 23. As herein disclosed, the 20 annular clamping member 26 is hingedly connected, as indicated at 27, to the flanged portion 23 and is provided at a point diametrically opposite to the hinged connection 27 with a pivoted handle member 29 provided with a slot or opening 30, through which is adapted to be projected the curved lip 31 projecting outwardly and radially from the annular member 22 at a point diametrically opposed to the pivotal connection 27. By this arrangement, it will be noted that when a sack or the like is inserted 25 through the annular member 22 and has its mouth passed over the flanged portion 23, the studs 25, when the clamping member 26 is adjusted into clamping position upon the flanged portion 23, will engage with the mouth of the sack or the like and effectively sustain the same in operative position when the handle member 29 is brought into engagement with the curved lip 31. The pivotal connection 27, hereinbefore referred to, is so positioned that when the clamping member 26 is swung to an open position it will contact with the buffer 8, hereinbefore 30 referred to, and thereby reduce to a minimum the possibility of breakage of the parts, as is believed to be self-evident.

As herein embodied, two of the tubular members 6 have secured thereto the substantially L-shape brackets 32, the offset or horizontal portions whereof having suitably secured thereto the eye-bolts 33, with each of which is suitably engaged a flexible member 34, preferably a linked chain, which has its opposite or upper extremity suitably connected with an eye-bolt 35 depending from an offset portion or ear 36 produced upon the adjacent sleeve 20. The remaining tubular member 6 has attached hereto a U-shape

bracket 37 with which is operatively engaged the lower extremity of a rod 38 and which is also disposed through an offset portion or ear 39 carried by the adjacent sleeve 20.

Projecting upwardly from the offset portion or ear 39 is a graduated member or bar 40 provided with an axial bore for the reception of the upper extremity of the rod 38 and whereby said rod 38 may serve as a guide for sustaining the graduated member 40 at all times in a vertical position. Co-acting with the member 40 is an index or indicator 41, herein disclosed as an annular member surrounding the same and having threaded therethrough the binding screw 42 whereby the index or indicator may be effectively sustained at a proper position upon the graduated bar 40 so that the exact amount of material to be weighed in the sack may be accurately determined.

The upper flanged portion 23 of the annular member 22 is provided with an extended finger or arm 43 which is adapted to coact with the index or indicator 41 in a manner and for a purpose which is believed to be self-evident.

While the operation of my device is thought to be clearly apparent in view of the foregoing description, it might be well to state that the threaded engagement between the rods 16 and the sockets 17 permits the same to be relatively adjusted to compensate for any yield in the springs 15 which may occur, and it will also be self-evident that the flexible elements 34 limit the upward movement of the annular member 22 and its concomitant parts.

From the foregoing description, it is thought to be obvious that a sack holding and weighing device constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described comprising a support including tubular members having their upper ends open, an inwardly disposed annular shoulder within each of the tubular members adjacent its open end, a disk rested upon said shoulder, a helical spring secured to and depending from the disk, the lower extremity of said

- spring being closed, a rod disposed through the disk and in contact with the closed end of the spring, sockets disposed within the tubular members and operatively engaged with the rods, and a clamping device operatively engaged with the sockets. 2. A device of the character described comprising a support including tubular members having their upper ends open, an inwardly disposed shoulder within each of the tubular members adjacent its open end, a disk rested upon said shoulder, a helical spring secured to and depending from the disk, the lower extremity of said spring being closed, a rod disposed through the disk and in contact with the closed end of the spring, sockets disposed within the tubular members and operatively engaged with the rods, a clamping device operatively engaged with the sockets, and means coacting with the support and certain of the sockets for limiting the upward movement of the clamping device relative to the support. 3. A device of the character described comprising a support including tubular members having their upper ends open, an inwardly disposed shoulder within each of the tubular members adjacent its open end, a disk rested upon said shoulder, a helical spring secured to and depending from the disk, the lower extremity of said spring being closed, a rod disposed through the disk and in contact with the closed end of the spring, sockets disposed within the tubular members and operatively engaged with the rods, a clamping device operatively engaged with the sockets, and flexible members operatively connected with certain of the sockets and the support for limiting the upward movement of the clamping device relative to the support. 4. A device of the character described comprising a support including tubular members having their upper ends open, an inwardly disposed annular shoulder within each of the tubular members adjacent its open end, a disk rested upon said shoulder, a helical spring secured to and depending from the disk, the lower extremity of said spring being closed, a rod disposed through the disk and in contact with the closed end of the spring, sockets disposed within the tubular members and operatively engaged with the rods, a clamping device operatively engaged with the sockets, and anti-friction means interposed between the sockets and the inner walls of the tubular members. 5. A device of the character described comprising a support including tubular members having their upper ends open, an inwardly disposed annular shoulder within each of the tubular members adjacent its open end, a disk rested upon said shoulder, a helical spring secured to and depending from the disk, the lower extremity of said spring being closed, a rod disposed through the disk and in contact with the closed end of the spring, sockets disposed within the tubular members and operatively engaged with the rods, a clamping device operatively engaged with the sockets, and an upstanding graduated member carried by one of the sockets, an indicator adjustable upon said graduated member, and a finger carried by the clamping device adapted to coact with the indicator. 6. A device of the character described comprising a support including tubular members having their upper ends open, an inwardly disposed annular shoulder within each of the tubular members adjacent its open end, a disk rested upon said shoulder, a helical spring secured to and depending from the disk, the lower extremity of said spring being closed, a rod disposed through the disk and in contact with the closed end of the spring, sockets disposed within the tubular members and operatively engaged with the rods, a clamping device operatively engaged with the sockets, an upstanding graduated member carried by one of the sockets, an indicator adjustable upon said graduated member, and a finger carried by the clamping device adapted to coact with the indicator. 7. A device of the character described comprising a support including tubular members having their upper ends open, an inwardly disposed annular shoulder within each of the tubular members adjacent its open end, a disk rested upon said shoulder, a helical spring secured to and depending from the disk, the lower extremity of said spring being closed, a rod disposed through the disk and in contact with the closed end of the spring, sockets disposed within the tubular members and operatively engaged with the rods, a clamping device operatively engaged with the sockets, an upstanding graduated member carried by one of the sockets, an indicator adjustable upon said graduated member, a finger carried by the clamping device adapted to coact with the indicator, and means carried by the tubular member for maintaining the graduated member in vertical position. 8. A device of the character described comprising a support including tubular members having their upper ends open, an inwardly disposed annular shoulder within each of the tubular members adjacent its open end, a disk rested upon said shoulder, a helical spring secured to and depending from the disk, the lower extremity of said spring being closed, a rod disposed through the disk and in contact with the closed end of the spring, sockets disposed within the tubular members and operatively engaged with the rods, a clamping device operatively engaged with the sockets, an upstanding

graduated member carried by one of the sockets, an indicator adjustable upon said graduated member, a finger carried by the clamping device adapted to coact with the indicator, said graduated member being provided with a bore, and a vertically disposed rod carried by the tubular member projecting within the graduated member

for maintaining said graduated member in vertical position.

In testimony whereof I hereunto affix my signature in the presence of two witnesses.

LOUIS GARNIER.
